UNITED STATES PATENT OFFICE

PERCY E. BARKER, OF SHAKER HEIGHTS, OHIO, ASSIGNOR TO THE CINDERELLA WASHING MACHINE COMPANY, OF CLEVELAND, OHIO, A CORPORATION OF OHIO

COMBINATION WASHING MACHINE AND DUST COLLECTOR

Application filed January 6, 1930. Serial No. 418,833.

The principle of the invention being herein explained, and the best mode in which I have contemplated applying that principle, so as to distinguish it from other inventions.

5 My invention particularly relates to washing machines of the type shown, described and claimed in U. S. Letters Patent No. 1,731,517, issued upon my invention in washing machines. In the instant invention I have so 10 reorganized a washing machine of this general type as to render the same adapted to serve both as a washing machine and as a dust collector. This reorganization is of a 15 very simple character and the necessary changes in the machine add very little to the cost in order to render it adaptable to both purposes, the machine also being changed over from one use to the other very quickly and conveniently.

20 The annexed drawings and the following description set forth in detail certain means embodying my invention, such means constituting, however, but one of the various mechanical forms in which the principle of 25 the invention may be illustrated.

In said annexed drawings:

Figure 1 is a central vertical sectional view of my improved combination washing machine and dust collector as adapted for use 30 as a washing machine;

Figure 2 is a fragmentary horizontal section, taken in the plane indicated by the line 2—2, Figure 1;

Figure 3 is a view similar to Figure 1 in 35 which the machine is set up for service as a dust collector;

Figure 4 is a bottom plan section, taken in the planes indicated by the line 4—4, Figure 1; and

40 Figure 5 is an elevation, upon a small scale, of the machine in use as a dust collector.

Referring to the annexed drawings in which the same parts are indicated by the same respective numbers in the several views,

45 I provide spaced outer and inner receptacles 1 and 2, respectively, which are separated at the sides by the chamber or passage 3 and at the bottom by the space 5, the main portion of the inner receptacle being open at the

50 bottom and closed at the top except for a cen-

tral opening 18 formed in the casing member 17, the inner receptacle as a whole including at its top a cover member 6 which is mounted upon the casing member 17, as hereinafter fully described. This cover 6 may conveniently be considered as part of the inner receptacle 2. The cover member 6 is formed with a peripheral rim 7 having an annular series of spaced beads 8 upon its bottom surface which are adapted to seat upon the rim or peripheral bead 9 formed upon the outer casing 1, whereby the cover member 6 and connected elements are supported upon the receptacle 1 but in such spaced relation as to provide a series of openings 10 to the atmosphere between the beads 8, which openings 10 communicate with the space 3 within the outer receptacle 1 and surrounding the inner receptacle 2.

Centrally mounted upon the top of the cover member 6 is a motor 11 having a downwardly-extended shaft 12 to the outer end of which is secured a fan body 13 having a series of blades 14. This fan 13 is contained within an upper chamber 27 separated from a washing chamber 28 by the casing member 17 which forms a diaphragm between the suction casing or fan chamber 27 and washing chamber 28 except for the central diaphragm opening 18 which is opposite the inlet side of the fan 13 or suction producing means. This washing or cleaning chamber is formed by the main or cleaning chamber portion of receptacle 2 in combination with receptacle 1. Bolts 15 and spacing members 16 serve to secure together the cover member 6 and the main casing member or cleaning chamber portion of the inner receptacle 2. Communication between the washing chamber 28 and the fan chamber 27 is not direct through the hole 18 but is baffled by a plate 19 secured by bolts 20 to the diaphragm 17 opposite the hole 18 so as to prevent the drawing of water and suds and clothes into the fan chamber 27.

The means so far described operate in accordance with the method explained in my said Patent No. 1,731,517, air being withdrawn from the chamber 28 by the action of the fan 13 and recirculated downwardly through the space 3 and under the bottom 100

edge of the receptacle 2 and passing upwardly through the water to cause a surging and regurgitation of the latter and hence the washing of the clothes. The withdrawal of the air from the top of the chamber 28 soon results in such a rise in the water level in said chamber and a consequent fall of water in the space 3 that the air seal is broken at the bottom of the receptacle 2 and air enters the chamber 28, as has been described, and as shown in Figure 1. The best operating conditions are obtained when substantially a definite amount of water is used and such a level is indicated by any suitable means, such as the bead 26 formed in the receptacle 1. Assuming that water is present to the depth of about seven inches, when the pressure within the washing chamber 28 becomes approximately one quarter of a pound lower than atmospheric pressure, the water will have been lowered in the space 3 to approximately the extent necessary to break the water seal. A substantial amount of air is drawn in suddenly in that way, which crowds or forces the body of water toward the center with agitating effect, since the air works upwardly in a ring-like area adjacent the outer wall of the receptacle 2. The inrush of air places an additional load on the constantly revolving fan 13 and decreases its speed, so that the pressure inside and outside of the chamber 28 is momentarily equalized, which permits the water to drop instantly in the chamber 28 and rise rapidly in the outer space or chamber 3. The rapid changes in pressure by the sudden breaking of the water seal causes agitation and regurgitation of the water to such an extent that the goods are thoroughly washed in a comparatively short time. When the washing is completed, the water can be dumped out of the receptacle 1 by lifting the latter and turning it up to discharge the water over the top. It will be hereinafter more fully mentioned that this washing machine finds its particular field for comparatively small washings, or in other words is a midweek or utility machine, so that the lifting of the receptacle 1 to discharge the water is practicable. When it is desired to utilize this machine as a dust collector, in the manner of the usual vacuum sweeper, a slight reorganization is necessary which will now be described. To this end a pipe section 23 is utilized, this section communicating with the chamber 28 at the inner end and with the atmosphere at the outer end and being passed through the diaphragm 17 and the cover member 6 and being positioned in the machine at all times, but closed at the outer end by any suitable device, such as a plug 24, when the machine is used for washing purposes. During the dust collecting operation, this pipe section 23 is utilized as part of an air and dust passage from without to within the machine

and thus constitutes a conduit means or inlet to the cleaning chamber 28. For this purpose it is adapted to receive a fitting 32 used in standard practice for securing a dust bag 31 to a pipe connection, and a fitting 34 utilized for securing a flexible tubing or air hose 35 to a pipe section. These fittings are secured to the pipe section 23 in any suitable manner such as bayonet locks 42 and 43, respectively. The flexible tubing 35 of any desired length is secured at the other end to a handle member 36 upon a suitable dust-collecting fixture 37. The entire operating mechanism thus far described, with the exception of the receptacle 1, is thus combined in a single unit, and preferably it is of a size and weight such as to make it readily portable, and to that end is provided with handles 25 secured to the cover member 6, as plainly shown in Figure 5. Before the device is used as a dust-collector, this entire portable unit is lifted out of the receptacle 1 and any suitable gasket means, such as an annular tubular rubber ring 33, for shutting off the communication between the space 3 and the chamber 28, is dropped into the receptacle 1, as plainly shown in Figure 3. The operating unit is then set down upon this gasket 33. The latter, in combination with the bottom of the receptacle 1, serves in effect as a tight bottom cover or closing means for the receptacle 2 during the dust-collecting operation. It will be seen that this gasket 33 cooperates with the sides of receptacles 1 and 2, as well as with the bottoms thereof, to form a means closing the space or passage 3 and to provide an air tight seal between receptacles 1 and 2, and that this seal is maintained sufficiently for the desired purpose by the weight of this portable unit. Upon operating the motor 11, air is exhausted from the washing and dust-bag chamber 28 and hence is replaced by air withdrawn through the fabric of the dust filtering bag 31 which in turn exhausts the air from the tubing 35 and results in pulling in air and dust through the cleaning fixture 37. As is well known, the standard dust filtering bags are substantially dust proof but not air proof so that the collected dust is retained in the bag 31 and the air passes therethrough into the fan or air withdrawing means 13, and out through the outlet formed by the tortuous channel from the fan to the space 3 and the space between the bead 9 and the rim 7. The space provided by the passages 10 has been increased, during the reorganization of the machine into a dust collector, by the seating of the bottom of the receptacle 2 upon the gasket 33 and hence there is no restriction to the free passage of the air from the fan blades 14 to atmosphere. Furthermore, this opening to atmosphere, which is designated by the number 40 in Figure 3, is increased during the cleaning oper- 130

ation, over and above what is necessary during the washing operation, by the particular construction of the cover member 6. This cover member is formed with a downwardly 5 extended flange 21 which is an extension of the peripheral rim 7, this flange having a series of spaced outwardly-extended ribs 22 which are disposed closely adjacent to the outer receptacle 1, but not in contact there- 10 with, as plainly shown in Figure 2, whereby the air from the fan blades 14, during the dust-collecting operation can pass freely upwardly between the flange 21 and the receptacle 1 and out through the opening 40 de- 15 spite the nearness of the ribs 22 to the said receptacle 1. These ribs 22 serve as pilots to insert the receptacle 2 in the receptacle 1 and serve to align the receptacle 2 during the dust-collecting operation, there being no 20 positive lateral retention of the receptacle 2 at the top, during the dust-collecting operation, as there is during the washing operation, when the irregular or shouldered portion connecting the flange 21 to the rim 7 en- 25 gages the bead 9 to retain the receptacle 2 against lateral movement. Furthermore, during the washing operation there is not much occasion for the escape of any great amount of air through the passages 10, the 30 latter acting merely as safety vents and the only noticeable effect therethrough being a slight pulsating action, the heated vapor being recirculated through the machine and the heat thus conserved.

35 When the machine is used as a washing machine, heated air and vapor are exhausted from cleaning chamber 28 into the suction chamber, and from there through space 3 back into chamber 28, fluid communicating 40 means between space 3 and chamber 28 being provided by the space between the bottom or lower end of inner receptacle 2 and outer receptacle 1.

It is apparent that the suction fan and 45 the passages leading out from the cleaning chamber to the open lower end of the inner receptacle constitute means providing fluid circulation through the cleaning chamber, whereby the heated air and vapor are circu- 50 lated and recirculated through the cleaning chamber. When the machine is converted into a dust collector, the ring 33 is used as a means for interrupting this fluid circulation by closing the passage 3 and for increasing the 55 outlet opening 40 to the atmosphere, the opened conduit 23 provides an air and dust inlet into the cleaning chamber, and the bag 28 in the cleaning chamber acts as a dust filtering means.

60 When using the device as a dust collector, it is often desirable to pull the machine around the floor and in order that this may be done by means of the tubing 35, without dumping over the machine, I form the receptacle 1 with a bracket or hook 39 over which

may be fastened a strap 38 passed around one end of a loop portion 44 formed in the tubing 35. To assist in the passage of the air through the fan 13 and the discharge thereof from the fan chamber 27, I preferably pro- 70 vide a vertical diaphragm 41, forming a spiral passage from the discharge side of the fan to the outer area of the fan chamber, as plainly shown in Figure 4, this diaphragm 41 being secured by a suitable flange to the 75 top of the diaphragm 17 and extending upwardly through the entire height of the fan chamber 27 and contacting at its upper end with the under surface of the cover member 6. 80

What I claim is:

1. A combination washing machine and dust collector comprising outer and inner spaced receptacles, the outer receptacle being open to the atmosphere adjacent the top thereof when the machine is used for washing, fluid communication being provided between the space between said receptacles and a chamber in the interior of said inner receptacle adjacent the bottom of the latter when the machine is used for washing, removable 90 means for shutting off said communication when the machine is used as a dust collector, means for withdrawing air from a portion of said chamber, means forming an air outlet to the atmosphere from the air 95 withdrawing means, means forming an air conduit from the exterior of said inner receptacle to the interior thereof and adapted for attachment to a dust filtering bag and an air hose, respectively, at its inner and outer ends, 100 and means for releasably closing said conduit.

2. A combination washing machine and dust collector, as in claim 1, characterized in that the two receptacles are separate and independent and in that all the mechanism, except the outer receptacle and the removable shut-off means, is combined in a portable 105 unitary member.

3. A combination washing machine and dust collector, as in claim 1, characterized 110 in that the air-withdrawing means is located adjacent the top of the inner receptacle and carried by the latter.

4. A combination washing machine and dust collector, as in claim 1, characterized 115 in that the air-withdrawing means comprise a motor mounted upon the inner receptacle, a motor shaft extended into the inner receptacle, a suction fan secured to said shaft, and a diaphragm in said inner receptacle having an opening opposite the inlet side of said fan.

5. A combination washing machine and dust collector comprising outer and inner spaced receptacles, the outer receptacle being open to the atmosphere adjacent the top thereof when the machine is used for washing, fluid communication being provided between the space between said receptacles and a chamber in the interior of said inner receptacle adjacent the bottom of the latter when the 125 130

machine is used for washing, removable means for increasing the size of the opening to the atmosphere and for shutting off said communication when the machine is used as a dust collector, means for withdrawing air 5 from a portion of said chamber, means forming an air outlet to the atmosphere from the air withdrawing means, means forming an air conduit from the exterior of said inner receptacle to the interior thereof and adapted 10 for attachment to a dust filtering bag and an air hose, respectively, at its inner and outer ends, and means for releasably closing said conduit.

6. A combination washing machine and 15 dust collector comprising outer and inner receptacles spaced at the bottom and sides, the inner receptacle having a cover with a peripheral rim adapted to seat upon the rim of the outer receptacle when the machine is used for 20 washing, means providing an opening to the atmosphere between the cover rim and the rim of the outer receptacle when the machine is used for washing, removable means for 25 closing the space between said receptacles at the bottom when the machine is used as a dust collector, a diaphragm in said inner receptacle subdividing the interior thereof into a washing and dust-bag chamber portion and 30 a fan chamber, a suction fan in said fan chamber and means for operating said fan, said diaphragm being formed with a hole opposite said fan, said fan discharging toward 35 said opening to the atmosphere, means forming an air conduit from the exterior of said inner receptacle to the interior thereof and adapted for attachment to a dust filtering bag and an air hose, respectively, at its inner and outer ends, and means for releasably closing 40 said conduit.

7. A combination washing machine and 45 dust collector comprising outer and inner receptacles spaced at the bottom and sides, the inner receptacle having a cover with a peripheral rim adapted to seat upon the rim of the outer receptacle when the machine is used for washing, means providing an opening 50 to the atmosphere between the cover rim and the rim of the outer receptacle when the machine is used for washing, removable means for closing the space between said receptacles at the bottom and for increasing the size of 55 said opening to the atmosphere when the machine is used as a dust collector, a diaphragm in said inner receptacle subdividing the interior thereof into a washing and dust-bag chamber portion and a fan chamber, a suction fan in said fan chamber and means for operating said fan, said diaphragm being formed with a hole opposite said fan, said 60 fan discharging toward said opening to the atmosphere, means forming an air conduit from the exterior of said inner receptacle to the interior thereof and adapted for attachment 65 to a dust filtering bag and an air hose,

respectively, at its inner and outer ends, and means for releasably closing said conduit.

8. A combination washing machine and 70 dust collector comprising outer and inner receptacles spaced at the bottom and sides, the inner receptacle having a cover with a peripheral rim adapted to seat upon the rim of the outer receptacle when the machine is used for washing, means providing an opening 75 to the atmosphere between the cover rim and the rim of the outer receptacle, removable means for closing the space between said receptacles at the bottom when the machine is used as a dust collector, a diaphragm in 80 said inner receptacle subdividing the interior thereof into a washing and dust-bag chamber portion and a fan chamber, a suction fan in said fan chamber and means for operating said fan, said diaphragm being formed with a hole opposite said fan, said fan discharging toward 85 said opening to the atmosphere, an open-ended pipe section extended through said cover exteriorly of the inner receptacle and also through said diaphragm interiorly of said washing and dust-bag chamber, and a removable plug for said pipe section.

9. A combination washing machine and 90 dust collector comprising outer and inner receptacles spaced at the bottom and sides, the inner receptacle having a cover with a peripheral rim adapted to seat upon the rim of the outer receptacle when the machine is used for washing, means providing an opening 95 to the atmosphere between the cover rim and the rim of the outer receptacle, removable means for closing the space between said receptacles at the bottom when the machine is used as a dust collector, a diaphragm in 100 said inner receptacle subdividing the interior thereof into a washing and dust-bag chamber portion and a fan chamber, a suction fan in said fan chamber and means for operating said fan, said diaphragm being formed with a hole opposite said fan, means in said fan chamber forming a tortuous air channel from 105 the discharge side of said fan to said opening to the atmosphere, an open-ended pipe section extended through said cover exteriorly of the inner receptacle and also through said diaphragm interiorly of said washing and dust-bag chamber, and a removable plug for 110 said pipe section.

10. A combination washing machine and 115 dust collector comprising outer and inner receptacles spaced at the bottom and sides, the inner receptacle having a cover with a peripheral rim adapted to seat upon the rim of the outer receptacle when the machine is used for washing, said peripheral rim having a depending flange extended into the outer receptacle and spaced from the latter, said depending flange being formed with spaced outwardly extended ribs positioned closely adjacent said outer receptacle but not touching the latter, the seating means upon said 120 pe-

ripheral rim comprising a plurality of spaced beads whereby a plurality of openings to the atmosphere are provided when the machine is used for washing, removable means for closing the space between said receptacles at the bottom when the machine is used as a dust collector, a diaphragm in said inner receptacle subdividing the interior thereof into a washing and dust-bag chamber and a fan chamber portion, a suction fan in said fan chamber and means for operating said fan, said diaphragm being formed with a hole opposite said fan, said fan discharging toward said openings to the atmosphere, an open-ended pipe section extended through said cover exteriorly of the inner receptacle and also through said diaphragm interiorly of said washing and dust-bag chamber, and a removable plug for said pipe section.

11. A dust collector comprising a receptacle having an open bottom, a diaphragm dividing said receptacle into a dust-bag chamber portion and a fan chamber and providing fluid communication therebetween, a suction fan in said fan chamber, means for operating said fan, said fan chamber having an outlet to the atmosphere, said dust-bag chamber portion having an inlet from the exterior of said receptacle, the inner end of said inlet being adapted for attachment to a dust-bag and the outer end thereof being adapted for attachment to a flexible tubing, and means adapted to effect an air tight seal between said open bottom of said receptacle and a closure element therefor merely by the weight of said dust collector.

12. A combination washing machine and dust collector comprising an outer receptacle having an open top; an inner receptacle adapted to fit in said outer receptacle in spaced relation to the bottom and sides thereof and adapted to rest upon the upper portion of said outer receptacle, said inner receptacle having an open bottom, a top cover carrying a fan and driving means therefor, a diaphragm spaced from said cover, and a fan chamber between said cover and said diaphragm, said diaphragm having an opening forming an inlet to said fan chamber and said fan chamber having an outlet to the atmosphere; conduit means from the outside of said inner receptacle into the interior thereof below said diaphragm; means adapted to close the space between said inner and outer receptacles; dust filtering means adapted to be associated with said conduit means; and means adapted to close said conduit means.

13. A combination washing machine and dust collector comprising an outer receptacle having an open top, an inner receptacle having its lower end formed so as to permit ready passage of washing liquid and removably fitted in said outer receptacle in spaced relation to the sides thereof, said receptacles forming a cleaning chamber, removable

means adapted to close the space between said receptacles, a suction casing carried by said inner receptacle, said casing having an outlet to the atmosphere, suction producing means in said casing, an inlet to said casing from said cleaning chamber, conduit means forming an air and dust passage from the atmosphere into said cleaning chamber, dust filtering means adapted to fit within said chamber and to be connected to said conduit means, and means adapted to close said conduit means.

14. In a combination washing machine and dust collector, an outer receptacle having an open top and being otherwise imperforate; an inner receptacle having an open bottom removably fitting in said outer receptacle to form a chamber therewith, an air outlet at its other end, an air and dust inlet, said inner receptacle being otherwise closed, and suction producing means between said inlet and said outlet; means forming an air tight seal between said receptacles; and dust filtering means in said chamber and removably connected to said air and dust inlet.

15. In a combination washing machine and dust collector, an outer receptacle having an open end; an inner receptacle adapted to fit in said outer receptacle and having a perforated diaphragm dividing said inner receptacle into a suction casing and a cleaning chamber portion, said cleaning chamber portion forming a cleaning chamber with said outer receptacle, said suction casing having an outlet, and said cleaning chamber portion having an inlet; dust filtering means adapted to fit within said cleaning chamber and to be connected to said inlet; and means adapted to form a gas tight seal between said outer and inner receptacles.

16. In combination, for a device constituting a combination washing machine and dust collector, a receptacle open at one end, means for closing the open end of said receptacle when the device is used as a dust collector, a diaphragm dividing said receptacle into a fan casing and a cleaning chamber portion, conduit means adapted to form an air and dust inlet into said cleaning chamber portion, and adapted for connection with means for removing dust from air when the device is used as a dust collector, means adapted to close said conduit means, when the device is used for washing, an air inlet being provided to said fan casing from said cleaning chamber portion, a fan in said fan casing, an air outlet from said fan casing, and means for operating said fan having a driving connection therewith.

17. A portable unit for a device constituting a combination washing machine and dust collector, said unit comprising a receptacle, a diaphragm dividing said receptacle into upper and lower portions, a suction casing in the upper portion, conduit means leading

- into the lower portion, said conduit means being adapted to be connected with dust filtering means when the device is to be used as a dust collector, means adapted to close said conduit means when the device is to be used 5 for washing, suction producing means in said suction casing, said diaphragm having an opening forming an air inlet into said suction casing from said lower portion, a motor carried by said receptacle and having a driving 10 connection with said suction producing means, and an outlet from said suction casing to the atmosphere.
18. In combination with a washing machine comprising an outer receptacle having an open top, an inner receptacle having its lower portion formed to permit the ready passage of cleaning fluid, said inner receptacle fitting removably in said outer receptacle with its sides spaced therefrom and forming a cleaning chamber with said outer receptacle, a suction casing in the upper portion of said inner receptacle, suction producing means in said casing, an outlet from said 20 casing, and an inlet to said suction casing from said cleaning chamber; means adapted to close the space between the sides of said inner and outer receptacles, conduit means forming a passage into said cleaning chamber, means adapted to close said conduit means, and a dust filtering bag adapted to be secured in said cleaning chamber with said conduit means communicating with its interior.
19. In combination with a washing machine comprising an outer receptacle having an open top, an inner receptacle having its bottom formed to permit the ready passage of cleaning fluid, said inner receptacle fitting removably in said outer receptacle with its bottom spaced therefrom and forming a cleaning chamber with said outer receptacle, a suction casing in the upper portion of said inner receptacle, suction producing means in said casing, an outlet from said casing, and an inlet to said suction casing from said cleaning chamber; means adapted to close the space between the bottoms of said inner and outer receptacles, conduit means forming a passage 40 into said cleaning chamber, means adapted to close said conduit means, and a dust filtering means adapted to be secured to said conduit means.
20. In combination with a washing machine comprising a cleaning chamber, a suction casing, means providing a passage leading from the atmosphere to the lower portion of the cleaning chamber, an opening being provided between said cleaning chamber and said suction casing, and an outlet from said suction casing; means adapted to close said passage, an inlet to said cleaning chamber, dust filtering means adapted to be connected to said inlet, and means adapted to close said 55 inlet.
21. In combination with a washing machine comprising a cleaning chamber, a suction casing communicating with said cleaning chamber, an outlet from said suction casing, and means providing a passage from said outlet to said cleaning chamber, means adapted to close said passage, an inlet to said cleaning chamber and a dust filtering bag adapted to be secured in said cleaning chamber with said inlet communicating with its interior. 70
22. In a combination washing machine and dust collector, an outer receptacle having an opening at one end; an inner receptacle having an open end fitting removably in said opening to form a cleaning chamber with said outer receptacle, a suction casing, an outlet therefrom to the atmosphere, suction producing means in said casing, and an air inlet to said casing from said cleaning chamber; a conduit adapted to provide an air and dust inlet to said cleaning chamber; a dust filtering bag adapted to fit in said cleaning chamber with its interior in communication with said conduit; and removable means adapted to form an air tight seal between the receptacles. 75
23. Means for converting a washing machine into a dust collector, said washing machine including a cleaning chamber, an inlet thereto, an outlet therefrom, and a fan; said means comprising means adapted to close said inlet, a conduit adapted to provide an air and dust inlet to said cleaning chamber, and filtering means adapted to be placed between said conduit and said outlet. 80
24. Means for converting a washing machine into a dust collector, said washing machine including a cleaning chamber, an inlet thereto, an outlet therefrom having an opening to the atmosphere, and a fan; said means comprising means adapted to close said inlet and to enlarge said opening to the atmosphere, a conduit adapted to provide an air and dust inlet to said cleaning chamber, and dust filtering means adapted to be placed between said conduit and said outlet. 85
25. Means for converting a washing machine into a dust collector, said washing machine including a cleaning chamber, suction producing means, and passages providing for fluid circulation through said chamber; said first-mentioned means comprising means adapted to interrupt said fluid circulation, a dust and air inlet adapted to have communication with said cleaning chamber, and dust filtering means adapted to be placed in said cleaning chamber. 95
26. Means for converting a washing machine into a dust collector, said washing machine including a cleaning chamber and means for providing fluid circulation through said cleaning chamber; said first-mentioned means comprising means adapted to interrupt said fluid circulation, an air and dust inlet adapted to have communication 100
- 110
- 115
- 120
- 125
- 130

with said cleaning chamber, and dust filtering means adapted to be attached to said air and dust inlet.

27. Means for converting a washing machine into a dust collector, said washing machine including a cleaning chamber and means for providing fluid circulation through said cleaning chamber, and said second-mentioned means including a passage from said chamber communicating with a passage leading to said chamber; said first-mentioned means comprising means adapted to close one of said passages and thereby to interrupt said fluid circulation, a conduit adapted to provide an air and dust inlet to said cleaning chamber, and dust filtering means adapted to be placed in said cleaning chamber.

28. Means for converting a washing machine into a dust collector, said washing machine including a cleaning chamber and means for providing fluid circulation through said cleaning chamber, and said second-mentioned means including a passage leading from said chamber and communicating with a passage leading to said chamber; said first-mentioned means comprising means adapted to close one of said passages and thereby to interrupt said fluid circulation, a conduit having one end communicating with said cleaning chamber and having its other end outside of said washing machine, and dust filtering means adapted to be placed in said cleaning chamber.

35 Signed by me this 31st day of December, 1929.

PERCY E. BARKER.
